(57) **CLAIM**

The ornamental design for a medical flow clamp, as shown
and described.

DESCRIPTION

FIG. 1 is a front side view of the medical flow clamp,
showing the new design;

FIG. 2 is a right side view thereof;

FIG. 3 is a back side view thereof;

FIG. 4 is a left side view thereof;

FIG. 5 is a top plan view thereof;

FIG. 6 is a bottom plan view thereof; and,

FIG. 7 is a front, top, left side perspective view thereof.
The ornamental design which is claimed is shown in solid
lines in the drawings. The broken lines in the drawings
depict portions of the medical flow clamp and form no part
of the claimed design.
